UNITED STATES PATENT OFFICE.

EDWARD HECKMANN, OF HERMANN, MISSOURI.

GAME APPARATUS.

1,267,220.

Specification of Letters Patent. Patented May 21, 1918.

Application filed April 23, 1917. Serial No. 163,847.

To all whom it may concern:

Be it known that I, EDWARD HECKMANN, a citizen of the United States, and a resident of Hermann, in the county of Gas-
5 conade and State of Missouri, have invented a new and Improved Game Apparatus, of which the following is a full, clear, and exact description.

My invention has for its object to pro-
10 vide a game apparatus having a board with a gate at one end, there being two sets of openings in the board beyond the gate, one set at each side of the board, the openings at one side of the board indicating de-
15 fensive plays and the penalty if the player does not make the attempted play, and the openings at the other side indicating offen-
20 sive plays with the penalty if the player does not succeed in making the play at-
tempted.

With this construction, the opposing play-
25 ers may assume positions side by side at the front of the gate; and first one of the play-
ers may shoot a marble through the gate
and across the board at an opening indicating a defensive play; and the other player may shoot through the gate and across the board in a similar manner.

Additional objects of the invention will
30 appear in the following specification in which the preferred form of the invention is disclosed.

In the drawings similar characters of ref-
35 erence denote similar parts in all the views, in which—

Figure 1 is a plan view showing the board used in playing my game, part being broken away to illustrate the construction;

Fig. 2 is a sectional view on the line 2—2
40 of Fig. 1; and

Fig. 3 is a transverse sectional view on the line 3—3 of Fig. 2.

By referring to the drawings, it will be seen that the game board has a rim 5 at its
45 sides 6 and 7 and also at its rear end 8, to prevent the marbles from rolling from the board 9. Near the front 10 of the board there is a gate 11, an opening 12 being made in this gate, through which the play-
50 ers shoot the marbles across the board. In front of the gate 11 there is a position 14 which is the position from which the player on the defensive shoots, this position having

the word "Pitcher" indicated thereon. An-
other position 13 at the left of the board 55 is the offensive position, and at this position there is indicated the word "Batter", the player shooting from the defensive position 14 being the first to play. This player shoots the marble through the opening 12 60 in the gate 11 to the left side 7 of the board. The players shoot alternately, the player assuming the offensive following the first player, and shooting through the opening 12 in the gate in the direction of the side 6 65 of the board. In playing the game, it is essential that the player make known the play for which he is about to attempt.

At the right of the board there is an opening 15, with a mark on the board indicating 70 that if the marble falls through this opening 15 the play will be a "hit". There is a smaller opening 16 to the right of the opening 15 with a mark on the board indicating that should the marble fall through 75 this opening 16, the play will be a "safe bunt" if the last marble pitched was a "ball". Beyond the opening 15, and somewhat nearer the center line of the board there is an opening 17, with a mark on the board indicating 80 that if the marble falls through this hole the play is a "foul strike". Some distance beyond the opening 17 there is an opening 18, with marks on the board indicating that should the marble fall through 85 this opening the play will be a "two base hit". Beyond the opening 18 there is an opening 19, with a mark on the board indicating that should the marble fall through 90 the opening 19, the play will be a "three base hit". There is also an opening 20 in the board near the center line of the board, with a mark indicating that should the marble fall through this opening 20 the play will be a "home run". Between the opening 95 17 and the opening 18 there is a zone 21 with a mark indicating that should the marble cross or enter this zone the batter will be "out". There is also a zone 22 between the openings 18 and 19, with a mark on the board 100 indicating that the batter will be out should the marble cross or enter this zone. Between the openings 19 and 20 there is an additional zone 23 with a mark on the board to the effect that should the marble cross or 105 enter the zone 23 the batter will be "out".

The player on the defensive shoots from the position 14 through the opening 12 in the gate, with the object of making a defensive play, the rules requiring that the 5 player indicate the play which he is about to attempt. Should the player not succeed in making the play which he has announced, he cannot be credited with a successful defensive play, and the penalty will be indicated by the zone over which the marble 10 passes or which marble enters.

The player on the offensive shoots from the position 13 indicated by the word "Batter," through the opening 12 in the gate in 15 the direction of the right side of the board. At the left side of the board there is an opening 24 with a mark on the board indicating that should the marble fall through the opening 24, the play will be a "strike." 20 There is an opening 25 in the board, with a mark on the board indicating that should the marble fall through the opening 25 the play will be a "ball." There is an opening 26 in the board, with a mark on the board 25 indicating that should the marble fall through the opening 26 the play will count as in the game of base ball when the batter is hit by a ball. There is an opening 27 in the board, with a mark on the board indicating that should the marble fall through the opening 27 the play will count as in base 30 ball when a batter is "out," at first base. There is an opening 28 in the board, with a mark on the board indicating that the base runner is "out" at second, should the marble fall through the opening 28. There is an opening 29 in the board, with a mark on the board indicating that should the marble fall through the opening 29, the base runner is 35 "out" at third base, with the same result as in the out-door game of base ball. In addition there is a zone between the opening 26 and the opening 27, with a mark on the board indicating that should the marble 40 cross or enter this zone the play will be the same as in the out-door game of base ball when the pitcher is charged with a balk when there is a man on base. There is a zone 31 between the openings 27 and 28, with 45 marks on the board indicating that if the marble crosses this space the base runner goes to second, if second base is not occupied. There is a zone 32 between the openings 28 and 29, with a mark on the board indicating 50 that should the marble cross this zone the runner goes to third base, if the third base is not occupied. In addition, there is a zone 33 with a mark on the board stating that the base runners will be advanced except from 55 third, when the marble crosses the said zone 33. There is a zone 39 with markings to indicate that the runner scores when a marble crosses this zone. In order that the positions of the base runners on the bases may be 60

indicated at all times, at one corner of the 65 board a base ball diamond 35 is indicated.

Below the board there is a return-way 36, and the bottom of the board is preferably inclined toward its front so that the marbles which fall through the openings which have 70 been referred to will be returned to the front of the board, there being a guide 37 on the return-way 36 which directs the marbles to the sides 6 and 7 of the board, which are extended at 38 and which are open at their tops 75 so that the marbles may be readily removed by the players.

The transverse opening 34 in the board does not indicate any play, it being provided to permit of "dead" marbles to fall through 80 the board.

Having thus described my invention, I claim as new, and desire to secure by Letters Patent:

1. In a game apparatus, a board having a 85 gate, and beyond the gate two sets of openings one set at each side of the board, the set of openings and marks on one side of the board indicating offensive plays and penalties if the player does not succeed in making 90 the attempted play, and the openings and marks on the other side of the board indicating defensive plays and penalties if the player does not succeed in making the attempted defensive play. 95

2. In a game apparatus, a board having two sets of openings one set at each side of the board, the sets of openings and marks at one side of the board indicating offensive plays and penalties if the player does not succeed in making the attempted play, and the openings and marks on the other side of the board indicating defensive plays and penalties if the player does not succeed in making the attempted defensive play. 100

3. In a game apparatus, a board having a gate, and beyond the gate two sets of openings one set at each side of the board, the set of openings and marks on one side of the board indicating offensive plays and penalties if the player does not succeed in making the attempted play, and the openings and marks on the other side of the board indicating defensive plays and penalties if the player does not succeed in making the attempted defensive play, two positions being indicated in front of the gate one for the player on the offensive which is on the opposite side of the board as the openings and marks indicating offensive plays, and the other position being for the player on the defensive. 110

4. In a game apparatus, a board, there being two sets of indicated plays on the board one set at each side of the board, the indicated plays at one side of the board being offensive plays and penalties if the player does not succeed in making the attempted 125

play, and the indicated plays on the other side of the board being defensive plays and penalties if the player does not succeed in making the attempted defensive play.

5 5. In a game apparatus, a board having a gate, and beyond the gate two sets of indicated plays one set at each side of the board, the set of plays at one side of the board in-

dicating offensive plays and penalties if the player does not succeed in making the attempted play, and the plays on the other side of the board indicating defensive plays and penalties if the player does not succeed in making the attempted defensive play. 10

EDWARD HECKMANN.
